UNITED STATES PATENT OFFICE.

THEODORE W. FOSTER, OF PROVIDENCE, RHODE ISLAND.

BRACELET.

No. 824,072.

Specification of Letters Patent.

Patented June 19, 1906.

Application filed January 6, 1906. Serial No. 294,933.

To all whom it may concern:

Be it known that I, THEODORE W. FOSTER, a citizen of the United States, residing at Providence, in the county of Providence and 5 State of Rhode Island, have invented a new and useful Improvement in Bracelets, of which the following is a specification.

This invention has reference to an improvement in bracelets, and more particularly 10 to an improvement in concealed hinges for bracelets.

The object of my invention is to improve the construction of a concealed hinge for bracelets, whereby a stronger and more durable concealed hinge is constructed than has heretofore been done.

My invention consists in the peculiar and 15 novel construction of a concealed hinge for bracelets with details of construction, as will 20 be more fully set forth hereinafter.

Figure 1 is a side view of a bracelet provided with my improved concealed hinge and showing the bracelet in the closed position in full lines and in the open position in broken 25 lines. Fig. 2 is an enlarged detail sectional view of the hinge end of the bracelet looking at the outside face of the hinge. Fig. 3 is an enlarged detail sectional view taken on line 3 30 of Fig. 2 and showing the hinge in the closed position. Fig. 4 is an enlarged detail sectional view similar to Fig. 3, showing the hinge in the open position. Fig. 5 is an enlarged detail view of one of the hinge members looking at the outside face of the member, and Fig. 6 is an enlarged detail view of 35 the other member of the hinge looking at the inside face of the same.

In the drawings, *b* indicates the upper semi-oval half, *c* the lower semi-oval half, and *d* 40 the concealed hinge of my improved bracelet.

The semi-oval halves *b* and *c* are constructed from a tube which is oval in cross-section. The upper half *b* has the end *b'* for the hinge and the end *b''*. The lower half *c* has the end *c'* for the hinge and the end *c''*. The ends *b'* and *c'* and the ends *b''* and *c''* coincide when 45 the bracelet is closed. The ends *b''* and *c''* may be provided with any of the well-known forms of catches adapted to hold the ends 50 together when the bracelet is closed.

My improved concealed hinge *d* consists of the members *e* and *g*. These members *e* and *g* are curved to conform to the contour of the bracelet and shaped to fit into the ends *b'* 55 and *c'* of the halves *b* and *c*. The member *e* of the hinge has a solid body portion *e'*, from

the end *e'* of which extends a central arm *e''*, having an end *e''*, in the concave face of which is a groove *e'''*, forming at one end a stop-shoulder *e''''*, all formed integral, as 60 shown in Figs. 3 and 5. The end *e''* is formed concentric with the center on which the hinge opens. The member *g* of the hinge has a solid body portion *g'*, from which extends the two side arms *g''* *g''*, supporting the semi- 65 circular cross-bar *g''''*, on the convex face of which is the stamped-up stop-teat *g''''*, all formed integral, as shown in Figs. 2, 4, and 6. The cross-bar *g''''* is formed concentric with the center on which the hinge opens. 70

The hinge is assembled by placing the cross-bar *g''''* of the member *g* in the concave face of the end *e''* of the arm *e''* on the member *e* in a position for the stop-teat *g''''* to enter the groove *e''''*, as shown in Figs. 2 and 3. The 75 members *e* and *g* of the hinge are now forced into the ends *b'* and *c'* of the bracelet into a position where the center on which the hinge opens coincides with the juncture of the ends *b'* and *c'* of the bracelet. The body portions 80 *e'* and *g'* of the hinge members are now secured in the ends *b'* and *c'* of the bracelet by solder or other means.

The opening movement of the bracelet is limited by the stop-teat *g''''* in the groove *e''''* 85 engaging with the stop-shoulder *e''''*, as shown in Fig. 4. The action of the stop-teat *g''''* on the stop-shoulder *e''''*, in conjunction with the ends *b'* and *c'* of the bracelet, also prevents the separation of the hinge members after the 90 same are secured in the bracelet.

By the use of my improved construction I 95 provide a bracelet with a strong and durable concealed hinge having only two parts, each of which is formed integral.

Having thus described my invention, I claim as new and desire to secure by Letters Patent—

1. In a hinged bracelet, a concealed hinge comprising a member having a solid body portion from the end of which extends a central arm having an end in the concave face of which is a groove forming at one end a stop-shoulder, and a member having a solid body portion from which extend two side arms 100 supporting a cross-bar having on its convex face a stamped-up stop-teat adapted to enter the groove and engage with the stop-shoulder in the first member to limit the opening movement of the hinge. 105

2. A concealed bracelet-hinge comprising a member *e* having a solid body portion *e'*

from the end e^2 of which extends a central arm e^3 having an end e^4 in the concave face of which is a groove e^5 forming at one end a stop-shoulder e^6 , and a member g having a solid body portion g' from which extend two side arms g^2 supporting a cross-bar g^3 on the convex face of which is a stamped-up stop-teat g^4 adapted to enter the groove e^5 and engage with the stop-shoulder e^6 to limit the opening movement of the hinge.

3. The combination with a tubular half b having the end b' and a tubular half c having the end c' of a bracelet, of a concealed hinge d composed of the members e and g , the member e having a solid body portion e' from the end e^2 of which extends a central arm e^3 having an end e^4 in the concave face of which is a

groove e^5 forming at one end a stop-shoulder e^6 all formed integral, and the member g having a solid body portion g' from which extend two side arms g^2 supporting a cross-bar g^3 on the convex face of which is a stamped-up stop-teat g^4 adapted to enter the groove e^5 and engage with the stop-shoulder e^6 to limit the opening movement of the hinge, all formed integral. 20 25

In testimony wheeof I have signed my name to this specification in the presence of two subscribing witnesses.

THEODORE W. FOSTER.
